(57) **CLAIM**

I claim the ornamental design for a capsule, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view taken from the top of a color embodiment of a capsule;

FIG. 2 is an elevation view of a side thereof; the opposite side view being a mirror image;

FIG. 3 is an elevation view of the front thereof; the rear view being a mirror image;

FIG. 4 is a plan view of the bottom thereof;

FIG. 5 is a perspective view taken from the top of an alternative embodiment of a capsule;

FIG. 6 is an elevation view of a side thereof; the opposite side view being a mirror image;

FIG. 7 is an elevation view of the front thereof; the rear view being a mirror image; and,

FIG. 8 is a plan view of the bottom thereof.
